COMPRESSOR

Nicolas Herzmark, Paris, France

Application May 29, 1939, Serial No. 276,462
In Great Britain May 28, 1938

4 Claims. (Cl. 230—185)

(Granted under the provisions of sec. 14, act of
March 2, 1927; 357 O. G. 5)

This invention relates to air or gas compressors and more particularly to compressors of small size adapted to be driven by internal combustion engines upon aircraft for compressing air into receivers or "bottles" from which the air can be drawn as required for operating engine-starters or for other purposes.

The invention has for its main object to provide an improved compressor of the two-stage type, having the low-pressure and high-pressure cylinders placed vertically and in line, with the two pistons connected together by means of a slotted crosshead reciprocating between vertical guides in the casing and having a sliding-die engagement with the crankshaft.

Another object is to provide for inter-stage cooling of the compressed air or gas by means of externally cooled passages formed in the engine casing and extending between shallow circular or annular spaces above and below the top and bottom ends of the cylinders.

A further object is to provide for interrupting the operation of the compressor when the air or gas pressure reaches a desired limit.

Other objects of the invention will appear from the subsequent description given with reference to the accompanying drawings, in which—

Fig. 1 is a sectional elevation of a preferred embodiment of the improved compressor.

Fig. 2 is a plan view in section on the broken line 2—2—2 of Fig. 1.

Fig. 3 is a part sectional elevation, viewed at right angles to Fig. 1, and showing a cut-out device in transverse section.

Fig. 4 is a sectional elevation of the cut-out device, viewed at right angles to Fig. 3.

Figs. 5, 6 and 7 are details of the cut-out device.

As shown in Figs. 1 and 2, the compressor has its low-pressure cylinder 11 arranged above and the high-pressure cylinder 12 below the crankshaft 13, the two pistons 14, 15 being of the trunk type and connected together by means of a slotted crosshead 16 reciprocating between vertical guides 17, 18 and having engagement with the rotating crank 13 by means of a sliding die 19. The crankshaft is rotatably mounted in bearings 20, 21, preferably of ball or roller type carried by the end plates 22, 23 which are bolted to the open sides of the block or casing 24; one of the end plates is provided with a stuffing box 25 through which the crankshaft projects for connection to the drive.

The two cylinders 11, 12 are formed by liners 55 pressed into cavities 26, 27 at the top and bottom

ends of the block or casing 24, the latter being a casting of light alloy and the cavities being themselves lined by barrels 28, 29 cast in the block; these barrels are shouldered at 30, 31 to engage the block and the liners respectively. The upper cavity 26, which receives the low-pressure cylinder or liner 11, is in communication with the atmosphere by way of a port 32 at one side, air being allowed to enter the cylinder from this cavity through ports 33 cut in the cylinder or liner 11 at a position corresponding to the bottom end of the piston stroke; the lower cavity 27, which receives the high-pressure cylinder or liner 12 within its barrel 29, is adapted to provide a sump for oil lubricating the working parts and serving to cool the high-pressure cylinder. The cross-head guides 17, 18, consisting of part-cylindrical shells, are also cast in the engine block, one on each side of the central openings for the crankshaft 13, the guides being secured in place by studs or rivets 34, as indicated in Fig. 2.

Interstage communication between the two cylinders 11, 12 is provided by tubes 35 cast in the block 24, these tubes being preferably arranged in pairs adjacent to the cross-head guides 17, 18, to which they are secured by brazing before being inserted in the mould for casting the block. In the operation of the compressor, the tubes 35 are efficiently cooled at the exposed side surfaces of the block which are shown provided with horizontal cooling fins 36; as seen in Fig. 1, these tubes are approximately vertical for a height corresponding to the space 35 within which the crosshead 16 moves but their ends are inclined inwardly towards the vertical axis of the cylinders inside the walls of the two cavities 26, 27, so as to connect with shallow circular or annular spaces 37, 38 respectively above and below the top and bottom ends of the cylinder liners. The lower ends of the tubes are preferably curved inwards towards the axis, so as to pass radially through the barrel 29; all the tubes may be brazed or otherwise connected to the cylinder barrels 28, 29, prior to insertion in the mould.

The liners 11, 12 are held in position in the barrels by cylinder heads 39, 40 screwed into the ends of the barrels. The low-pressure cylinder head 39 is formed with a circular recess 41 on its lower face, the edge of this recess being chamfered at 42 to engage the bevelled edge 43 of a valve plate 44 secured by a central screw 45 to a cover plate 46 which rests upon the top end of the liner 11; within the shallow annular

space 47 between the plates 44, 46, there is mounted a delivery valve 48 of the annular disc type, made for example of bronze about 0.4 m/m. thick. Holes 49 in the cover plate 46 are normally sealed by this valve disc, but upon the rise of the piston 14 the pressure in the cylinder 11 lifts the valve from its seating so that the air can pass by way of radial ports 50 to holes 51 in the valve plate 44; these holes, which are approximately in line with the holes 49, communicate with the recess 41 of the cylinder head, and by way of a central opening 52 in the latter with the space 31 leading to the tubes 35, a cap nut 53 being screwed upon the exterior of the barrel 28 to enclose the space 31.

The high-pressure cylinder head 40, screwed into the barrel 28, carries two disc valves, one 54 of annular shape controlling the transfer of air from the annular space 38 fed by the tubes 35 into the high-pressure cylinder, and the other 55 of circular shape to control the delivery of high-pressure air. The annular valve 54 is mounted in a recessed valve plate 56 bearing against the bottom end of the liner 12, and this valve rests normally upon a cover plate 57; aligned holes 58, 59 in the two plates 56, 57, and radial ports 60 in the recessed portion of the valve plate 56, allow the air to pass upwards into the cylinder when the valve lifts upon the upward movement of the piston 15. The holes 59 in the cover plate 57 communicate with the annular space 38 by way of a circular trough 61 formed in the cylinder head 40 and radial holes 62 through the outer wall of this trough.

The valve plate 56 has a tubular boss 63 extending downwards through the cover plate 57 and cylinder head 40, within which boss the delivery valve 55 is located; the valve rests normally against a perforated seating 64, being held up by a coiled spring 65 surrounding the shouldered and perforated extremity of a hollow plug 66 screwed into the boss 63. When the valve 55 lifts under the pressure of air in the high-pressure cylinder, the air passes through the perforated sides and along the bore of the plug 66 into the space 67 within the lower end of the barrel 28, which is closed by a screw-threaded plug 68. The cylinder head 40 is provided with a packing ring 69, compressed by a ring nut 70, to prevent leakage of the high-pressure air along the screw-threads of the cylinder head and thus back into the trough 61 which contains air at lower pressure.

The air leaves the space 67 by way of aligned holes 71, 72 in the barrel 28 and casing 24, these holes leading into a port 73 in a cut-out device or safety blow-off shown in sectional views in Figs. 3 and 4. From the port 73 there extends a vertical passage 75 controlled by a non-return valve 76 of disc type, leading to a delivery pipe 77 connected to the air receiver or "bottle" (not shown).

In order to interrupt the operation of the compressor when the delivery pressure reaches the desired limit, the cut-out device is arranged to open a passage for the escape of the high-pressure air to the atmosphere, without however allowing discharge of air back from the delivery pipe 77. The cut-out device comprises a body 78 bolted to the side of the casing 24 beneath the stuffing box 25; the port 73 is formed in the face making contact with the side of the casing, and the delivery pipe 77 is coupled to the base by means of a union 79 screwing into a fitting 80 which also forms a housing for the non-return valve 76 and its spring 81. Holes 82 in the inner

end of this fitting allow the air pressure within the delivery pipe 77 to pass into two ducts 83, 84, formed in the cut-out body 78 and extending to the outer ends of a pair of small cylinders 85, 86 of slightly different diameter; these cylinders may be of diameters of 10 m/m. and 11 m/m. respectively, and their ends are closed by screw plugs 87. Two pistons 88, 89 working within the cylinders are connected together by a piston rod 90 having rack-teeth 91 formed along the central portion of its length; the smaller piston 89 is engaged by a spring 92, the force of which is just sufficient to prevent movement of the two pistons when both are subjected to the same pressure, until that pressure reaches the limit set for the delivery, whereupon the spring yields and allows the pistons to move towards the right hand side of Fig. 4.

The rack teeth 91 engage with a partly toothed wheel 93 secured upon a spindle 94 mounted in the body 78; the upper half of this wheel is formed with hexagonal faces 95, upon one of which there rests a spring plunger 96 mounted in the top of the body, the plunger acting to ensure a snap-movement of the wheel when actuated in either direction by the piston rod 90. The spindle 94 also carries a segmental valve-plate or shutter 97 having a port 98 and resting against a flat facing 99 in which there is formed a port 100; the port 98 is adapted to register with the port 100 in one position of the spindle 94, viz. when the delivery air pressure has caused the pistons 88, 89 to move against the spring 92, the air then escaping to the atmosphere through holes 101 in the cover 102, but normally the two ports are out of register so that the air cannot escape.

It will be noted that when the shutter 97 allows the escape of air, it is only the air from the high-pressure cylinder of the compressor which can travel by way of the ports 98, 100 and holes 101 to the atmosphere, but that the air from the delivery pipe 77 although having access to the cylinders 85, 86 by way of the ducts 83, 84, cannot so escape. As soon as the delivery pipe pressure falls, due for example to consumption of air for starting an engine, the pistons 88, 89 return to normal position, causing the shutter 97 to close the port 100. The spring plunger 96 forms a latching device which tends to hold the wheel 93 in one or other of its extreme positions, thereby preventing any "hunting" of the shutter 97.

The annular disc valves 48, 54 are preferably formed with spring tongues by slitting them radially from the outer periphery and along concentric but interrupted arcs intersecting or meeting the radial slits, so as to ensure uniform seating. In this and other respects, the design and material employed may be such as the judgment of the manufacturer dictates.

I claim:

1. A two-stage compressor, comprising high-pressure and low-pressure cylinders, pistons reciprocating in said cylinders, a crankshaft, a crosshead engaged by said crankshaft and connected to said pistons, guides for said crosshead, interstage communication passages between the outer ends of said cylinders, valve-fitted cylinder heads secured at the opposite ends of said cylinders, a delivery passage from said high-pressure cylinder, and a cut-off device including piston mechanism controlling an escape from said delivery passage and a latching device tending to hold said piston mechanism in one or other of its extreme positions.

2. A two-stage compressor, comprising high-

pressure and low-pressure cylinders, pistons reciprocating in said cylinders, a crankshaft, a crosshead engaged by said crankshaft and connected to said pistons, guides for said crosshead, interstage communication passages between the outer ends of said cylinders, valve-fitted cylinder heads secured at the opposite ends of said cylinders, a delivery passage from said high-pressure cylinder, and a cut-off device controlling an escape from said delivery passage, said cut-off device including two aligned cylinders of slightly different diameter, a pair of connected pistons reciprocable in said cylinders and both subjected to the pressure of air from said high-pressure cylinder, a shutter operated by said connected pistons and normally closing said escape from said delivery passage, and means for delaying the operation of said shutter by said pistons upon variation of said pressure.

3. A two-stage compressor, comprising high-pressure and low-pressure cylinders, pistons reciprocating in said cylinders, a crankshaft, a crosshead engaged by said crankshaft and connected to said pistons, guides for said crosshead, interstage communication passages between the outer ends of said cylinders, valve-fitted cylinder heads secured at the opposite ends of said cylinders, a delivery passage from said high-pressure cylinder, and a cut-off device controlling the operation of said compressor, said cut-off device including piston mechanism operated by the pressure of air from said high-pressure cylinder and means for delaying the action of said cut-off device upon variation of said pressure.

5 10 15 outer ends of said cylinders, valve-fitted cylinder heads secured at the opposite ends of said cylinders, a delivery passage from said high-pressure cylinder, and a cut-off device controlling an escape from said delivery passage, said cut-off device including piston mechanism operated by the pressure of air from said high-pressure cylinder and means for delaying the action of said cut-off device upon variation of said pressure.

4. A two-stage compressor, comprising high-pressure and low-pressure cylinders, pistons reciprocating in said cylinders, a crankshaft, a crosshead engaged by said crankshaft and connected to said pistons, guides for said crosshead, interstage communication passages between the outer ends of said cylinders, valve-fitted cylinder heads secured at the opposite ends of said cylinders, a delivery passage from said high-pressure cylinder, and a cut-off device controlling the operation of said compressor, said cut-off device including piston mechanism operated by the pressure of air from said high-pressure cylinder and means for delaying the action of said cut-off device upon variation of said pressure.

NICOLAS HERZMARK.
